UNITED STATES PATENT OFFICE.

SAM J. WARLICK AND JAMES H. BUNKER, OF KIOWA, KANSAS.

DEVICE FOR TRUING SPHERICAL BODIES.

1,156,953.

Specification of Letters Patent.

Patented Oct. 19, 1915.

Application filed November 12, 1913. Serial No. 800,667.

To all whom it may concern:

Be it known that we, SAM J. WARLICK and JAMES H. BUNKER, citizens of the United States, residing at Kiowa, in the county of Barber, State of Kansas, have invented certain new and useful Improvements in Devices for Truing Spherical Bodies; and we do hereby declare the following to be a full, clear, and exact description of the invention, 10 such as will enable others skilled in the art to which it appertains to make and use the same.

This invention relates to devices for truing spherical bodies and particularly adapted 15 for truing billiard balls.

The object of the invention resides in the provision of a device of the character referred to through the instrumentality of which a billiard ball may be rendered a true 20 sphere with ease and facility and in a comparatively short time.

A further object of the invention resides in the provision of a device of the type named which is adapted to effect not only 25 the truing of a billiard ball but also the finishing and polishing of same after it has been trued.

A still further object of the invention resides in the provision of a device of the 30 character named which will be simple in construction and which may be manufactured and sold at a comparatively small cost.

With the above and other objects in view 35 the invention consists in the details of construction and in the arrangement and combination of parts to be hereinafter more fully described and particularly pointed out in the appended claims.

40 In describing the invention in detail reference will be had to the accompanying drawings wherein like characters of reference denote corresponding parts in the several views, and in which—

45 Figure 1 is a view in elevation of the device with the cover in section; Fig. 2, a section on the line 2—2 of Fig. 1 with a billiard ball operatively associated therewith; Fig. 3, a view similar to Fig. 2 showing the 50 cutting ring reversed in position so as to permit of polishing the trued billiard ball,

and Fig. 4, a detail perspective view of the cutting and polishing ring.

Referring to the drawings the device is shown as comprising a base 10 having a circular recess 11 formed in the top thereof. The bottom of this recess 11 is provided with a dished portion 12. Removably seated in the recess 11 is a cutting and polishing ring 13. This ring is of a size to snugly 55 seat in the recess 11 and when so seated a portion of the ring will extend a slight distance above the top of the base 10. One end of the ring 13 is provided with an annular groove 14 and the portion of the ring between the annular groove and the inner wall 60 of the ring is ground to form an annular inwardly directed cutting edge 15.

In the use of the device the ball to be trued is placed within the ring 13 as shown 70 in Figs. 1 and 2, the diameter of the annular cutting edge 15 being less than the diameter of the ball, indicated at B, it will be obvious that the cutting edge will engage the surface of the ball at just one side of the widest 75 portion of the latter. The ball is then lapped by the index fingers and thumbs of both hands, the fingers lying over the ball on the far side and the thumbs over the near side. The hands are then moved to rotate 80 the ball toward the operator through the medium of engagement of the palms of the hands with the ball. During this operation the cutting edge 15 will trim and true the ball. In order to polish the ball after same 85 is cut the ring is reversed as shown in Fig. 3 and the ball rotated and applied as before. The inner edge of the end of the ring with which the ball is engaged in Fig. 3 being comparatively dull and smooth will efficiently 90 polish the ball.

The device is provided with a cover 16 suitably recessed to receive the upper portion of the ring 13, the ring thereby serving as a means for holding the cover against 95 lateral movement.

What is claimed is:—

1. In a device of the class described the combination of a base having a circular recess formed in its top and said recess having its bottom dished centrally, a ring removably seated in said recess, and an in-

ward directed annular knife element formed integral with the ring at one end thereof.

2. In a device of the class described, the combination of a base having a circular recess formed in its top, and a ring removably secured in said recess and having an inwardly directed annular knife element.

In testimony whereof, we affix our signatures, in the presence of two witnesses.

SAM J. WARLICK.
JAMES H. BUNKER.
